UNITED STATES PATENT OFFICE.

FREDERICK GOERTZ, OF NEWARK, AND RUSSELL WHITCOMB, OF ELIZABETH, NEW JERSEY.

CONTAINER.

1,345,360.

Specification of Letters Patent. Patented July 6, 1920.

Application filed February 12, 1920. Serial No. 358,093.

To all whom it may concern:

Be it known that we, FREDERICK GOERTZ and RUSSELL WHITCOMB, citizens of the United States, residing at Newark, in the county of Essex and State of New Jersey, and residing at Elizabeth, county of Union, and State of New Jersey, respectively, have invented certain new and useful Improvements in Containers; and we do hereby 5 declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to an improved case or box for toilet preparations; and the invention refers, more particularly to a novel compartment box provided with novel sealing means separating or dividing the compartments against escape of the contents thereof from one to the other when the box is closed, and consequently intermixture of different toilet preparations contained in the several compartments.

The invention has for its principal object 20 to provide a simple compartment box to contain variously colored rouge and face-powder, in the form of compacts or cakes or other desired form, ready for use, and separated from each other by a novel sealing means adapted to co-act with the box-cover, when the latter is closed, to seal the compartments against the escape of the preparations from their respective compartments into any of the other compartments, thereby 25 preventing preparations of one color being spoiled by intermixture or mingling with preparations of another color; as, for example, white face powder being spoiled by intermixture with red or pink rouges, or vice versa.

Other objects of the present invention, not at this time more particularly enumerated, will be clearly understood from the following detailed description of the same.

With the various objects of the present invention in view, the same consists, primarily, in the novel compartment box with the novel sealing means separating said compartments hereinafter set forth; and, the invention consists, furthermore, in the novel

arrangements and combinations of the seal-out devices and parts, as well as in the details of the construction of said parts, all of which will be more fully described in the following specification, and then finally embodied in the appended claims.

The invention is clearly illustrated in the accompanying drawings, in which:

Figure 1 is a plan view of the novel compartment box showing one embodiment of the principles of the present invention, the same being shown with its cover or lid open and the contents exposed.

Fig. 2 is a central longitudinal vertical section of the same, drawn on an enlarged scale, but showing the cover or lid in closed position.

Fig. 3 is a transverse vertical section, taken on line 3-3 in said Fig. 2.

Fig. 4 is a perspective view of a detachable compartment partition means adapted to support the novel sealing means for co-operation with the cover or lid of the box when the same is closed.

Fig. 5 is a plan view of the novel compartment box provided with a modified construction and arrangement of partition means adapted to support the desired sealing means.

Fig. 6 is a perspective view of said modified partition means detached from the box.

Similar characters of reference are employed in all of the above described views to indicate corresponding parts.

Referring now to said drawings, the novel compartment box comprises a main body having a bottom 1 and side walls 2 providing a receptacle which is preferably of elongated shape. A cover or lid 3 is suitably connected, by means of any desired construction of hinge connection 4, with the rear side wall of said main body, so as to be capable of being closed down over the open main body. The front side wall of said main body is provided with a nosing or projection 5, which is engageable by a catch-tongue 5' carried by said cover or lid, when the latter is closed, thereby retaining said cover or lid against accidental opening. Arranged within the under or interior side of 105 said cover or lid 3 is an inlay 6, having an intermediate symmetrically positioned rectangular opening 7 surrounded by an outwardly off-set frame or holding lip 8. Disposed intermediate said inlay 6 and said cover or lid 110

3, so that its marginal edges are fitted into and engaged by said off-set frame or holding lip 8 is a mirror 9, the reflecting face of which is thus exposed through the inlay 6 opening 7.

5 Fixed to the bottom 1 of said main body, so as to project upwardly therein is a centrally positioned transversely extending vertical lug 10. The interior of the main body 10 is divided transversely by means of a novel 15 U-shaped partition member 11 into two compartments 13 and 14, one of which, as 13, is adapted to contain a compact or cake of rouge 15, and the other of which, viz 14, is 20 adapted to contain a compact or cake of face-powder 16. Said U-shaped partition member 11 is provided in its bottom portion 17 with an opening or slot 18 adapted to receive said lug 10, when the partition member 25 is arranged in properly assembled relation to the main body, said lug serving to anchor said partition member in place, so that the same is securely held against accidental displacement. Connected with the upper 30 edges of the sides of said partition member are outwardly and oppositely extending horizontal flanges 19, which respectively overhang the interiors of said compartments 13 and 14, and which possess arc-shaped 35 outer peripheries 20, the latter being engaged over the adjacent margins of the compacts or cakes in said respective compartments. Said U-shaped partition member provides a channel or holding groove 21, into which is 40 wedged, so as to be securely held thereby, a sealing strip 22, preferably made of felt, cork, rubber, leather or some material possessing a requisite degree of resiliency. The upper free edge 23 of said sealing strip 22 45 projects freely upward above the partition member, so as to be engaged by the lid elements when said lid is closed. When the cover or lid is closed down upon the main body, the free edge 23 of said sealing strip 50 55 yieldingly engages the inner surface of the cover or lid, and so yielding, by reason of its inherent resiliency, tends to conform to the inner surface of the lid or cover as defined by the inlay 6 with its opening 7 and 60 holding lip 8 and by the surface of said mirror 9, thus interposing between the respective compartments and their contents a sealed obstruction, whereby any tendency of the contents of the respective compartments 65 to escape into the neighboring compartment is prevented, so that all danger of intermingling of the contents of said compartments to their detriment is eliminated, all of which will be clearly understood from an 70 inspection of Figs. 2 and 3.

Referring now to Figs. 5 and 6, there is illustrated therein a compartment box or case, embodying a mechanical variation or modification of the principles of the present invention. In said figures the reference

character 24 indicates the main body of a box or case to which is hinged a cover or lid 25, the latter being provided with the inlay 6 having the opening 7 and holding lip 8 for securing within the same the mirror 9. The 70 interior of the box or case is divided by a partition frame comprising a pair of substantially semi-circular U-shaped partition portions 26, the respective free ends of which are extended to meet or abut the 75 respective end walls of the box or case, thus respectively serving to inclose the compartments 27 and 28, adapted to respectively contain a rouge compact or cake 15 and a face powder compact or cake 16. The said 80 U-shaped partition portions 26 provide channels or grooves in which are received and retained resilient sealing strips 29 made of felt, cork, rubber, leather or some such resiliency material, said sealing strips bounding the inner sides of said compartments, and yieldingly engaging with their upper free edges the inner surface of the cover or lid, when the latter is closed, to seal the 85 respective compartments against the escape of 90 any portion of their contents, for the purposes already above described. Said U-shaped partition portions 26 may be joined together in proper mutual relation to the compartment spaces to be bounded thereby, 95 by means of longitudinal side members or plates 30, which, if desired may also serve to partition off relative to the longitudinal side walls of the main body 24, longitudinal compartments 31 and 32, adapted to receive and 100 hold a lip stick 33 and eye brow pencil 34, as shown, said articles being also protected, when the case is closed, against undesired contact with powdery or flaky sheddings of the compacts or cakes 15 and 16 by the sealing strips 29, all of which will be clearly understood from an inspection of Fig. 5 of the drawings.

We are aware that some changes may be made in the general arrangements and combinations of the several devices and parts, as well as in the details of the construction thereof, without departing from the scope of the present invention as set forth in the foregoing specification, and as defined in the 115 following claims. Hence, we do not limit our invention to the exact arrangements and combinations of the said devices and parts as described in the said specification, nor do we confine ourselves to the exact details of 120 the construction of the said parts as illustrated in the accompanying drawings.

We claim:—

1. A box having a lid for closing the same, partition means within said box to divide the same into a plurality of compact-receiving compartments, and said partition means having arranged therewith a resilient sealing strip adapted to engage and co-act 125 with the inner side of said lid to seal said 130

- compartments one from the other when said lid is closed.
2. A box the interior of which provides a plurality of compact-receiving compartments, a cover for said box, and a resilient sealing means intermediate said compartments adapted to engage and co-act with said cover to seal said compartments one from the other when said cover is closed.
- 10 3. A box having side walls, a cover for said box, a U-shaped partition member arranged to divide said box into a plurality of compact-receiving compartments, a resilient sealing strip anchored within the embrace of said U-shaped partition member, and said sealing strip having an upwardly projecting free edge adapted to engage and co-act with said cover to seal said compartments one from the other when said cover is closed.
- 15 4. A box having side walls, a U-shaped partition member arranged to divide said box into a plurality of compact-receiving compartments, a resilient sealing strip anchored within the embrace of said U-shaped partition member, said sealing strip having an upwardly projecting free edge, a cover for said box, an inlay arranged with the inner surface of said cover, said inlay having a central opening surrounded by an offset holding lip, and a mirror intermediate said inlay and said cover secured in said inlay opening by the embrace of said holding lip, said upwardly projecting free edge of said sealing strip yieldingly engaging and conforming to said inlay and mirror when said cover is closed to thereby seal said compartments one from the other.
- 20 5. A box having side walls, a cover for said box, a perpendicular holding lug within said box secured to the bottom thereof, a U-shaped partition member having an opening in its bottom portion adapted to receive said lug to engage said partition member therewith, said partition member dividing said box into a plurality of compact-receiving compartments, a resilient sealing strip anchored within the embrace of said U-shaped partition member, and said sealing strip having an upwardly projecting free edge adapted to engage and co-act with said cover to seal said compartments one from the other when said cover is closed.
- 25 6. A box, partition means within said box to divide the same into a plurality of compact-receiving compartments, said partition means having arranged therewith a resilient sealing strip provided with an upwardly projecting free edge, a cover for said box, a mirror, and means for retaining said mirror on the inner side of said cover, said upwardly projecting free edge of said sealing strip yieldingly engaging and conforming to said cover with its mirror and mirror retaining means when said cover is closed to thereby seal said compartments one from the other.
- 30 In testimony, that we claim the invention set forth above we have hereunto set our hand this 17th day of January, 1920.
